CONTAINER CLOSURE

Oscar W. Wentz, Long Island City, N. Y.

Application March 1, 1937, Serial No. 128,352

8 Claims. (Cl. 229—47)

This invention relates to closures for containers such as containers made of paper, cardboard, or the like, and particularly to liquid-carrying containers of that type.

One of the objects of this invention is to provide a simple, inexpensive and dependable device for maintaining closed the end of a container of the above-mentioned type, and one that will be capable of easy association with the container. Another object is to provide a device of the above-mentioned character that will be economical in its utilization of the raw material out of which it is made. Another object is to provide a device of the above-mentioned character which will be capable of speed and ease of manipulation, both for effecting the closure of the container and for effecting opening of the container. Another object is to provide a device of the above-mentioned character that will be efficient in action and that will dependably and in a simple way cope with certain peculiarities sometimes met with in practice, such as differences in the number of thicknesses of container material that happen to be folded and with which the device is to coact. Another object is to provide a compact and light but strong device made of a sheet material, such as sheet metal, capable of dependable and strong closure-retaining action throughout the closed or folded end of the container. Another object is to provide a device of the above-mentioned character that will be well adapted to meet the various conditions of hard practical use. Other objects will be in part obvious or in part pointed out hereinafter. The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention,

Figure 1 is a front elevation of a container showing my device applied thereto, before closure of the container;

Figure 2 is a plane view, as seen from above in Figure 1, showing also an illustrative form or method of folding the open end of the container to effect closure;

Figure 3 is a vertical transverse section as seen along the line 3—3 of Figure 1;

Figure 4 is a front elevation, like that of Figure 1, but showing the device and container in a stage of its manipulation;

Figure 5 is a vertical sectional view, as seen along the line 5—5 of Figure 4;

Figure 6 is a front elevation like that of Figures 1 and 4 but showing the device and container in its final stage;

Figure 7 is a plan view, as seen from above in Figure 6;

Figure 8 is a sectional view, as seen along the line 8—8 of Figure 6, and

Figure 9 is a plan view of a blank or strip of sheet metal showing how the preferred form of my invention lends itself to stamping or cutting, without wastage, out of the blank.

Similar reference characters refer to similar parts throughout the several views in the drawings.

Referring first to Figure 1, I have there shown a container generally indicated by the reference character 10, and to better illustrate certain features of my invention, it may be assumed that the container 10 is of suitably heavy paper, cardboard, or the like, and that it may be intended for the dispensing of liquid, such as milk. The container 10 may of itself be of any suitable or appropriate form or construction and is provided at its other and otherwise open or filling end with suitable or appropriate fold or crease lines whereby that end may be folded in any suitable way, preferably to bring its upper edges in alinement along a straight line, to effect a closure. Illustratively and as is better shown in Figure 2, these fold or crease lines may be such as to define front and rear panels 11 and 12 and lateral and opposed panels capable of being folded inwardly, for example, into double folds 13 and 14, the latter being received between the opposed panels 11, 12. When the upper edge portions of the panels 11, 12 are brought completely together, the double folds 13, 14 are at their upper ends snugly received between their opposed panels 11, 12, the upper edges of all of the panels and folds being brought substantially into alinement along a straight line. In Figure 2 the illustrative construction is shown only partly closed.

One of the panels, illustratively the front panel 11, preferably has an upward extension or flap 15 preferably defined as is better shown in Figure 1 by a horizontal fold or crease line 16. Flap 15 is of a suitable or appropriate width, as will later become clear.

To the front face of the flap 15, as viewed in Figures 1 and 2, is secured the retaining device generally indicated by the reference character 17. The device 17 is preferably made of a sheet ma- 55

material having appropriate characteristics whereby it may be relatively easily bent and when bent retaining the shape into which it is thus bent. Preferably, it is made of a suitable sheet metal.

5 Its preferred shape is well indicated in Figure 1; it comprises a horizontal portion 18 of a width commensurate with or slightly less than that of the flap 15 and a symmetrically shaped and positioned horizontal portion 19, both adapted to rest 10 against the flap 15, as shown in Figures 1 and 2. The portions 18 and 19 are joined by an intermediate V-shaped portion 20 which preferably extends downwardly a substantial distance below the flap 15, as is best shown in Figures 1 and 3, 15 and each portion 18 and 19 is extended, as at 22 and 23, to form tongues that project laterally beyond the side edges of the front panel 11.

The device 17 is secured in place and illustratively to the flap 15 by any suitable or appropriate means. Illustratively, the portions 18 and 19 thereof may have stamped or cut and bent out of their respective planes prong-like tabs 24 and 25, respectively, which, as is better shown in Figure 2, may be passed through the material of 25 the tab 15 and bent over, preferably in opposite directions from each other, and thus secure or clamp the container portion and the device 17 together.

When the container 10 has been filled, illustratively as in an over-the-counter sale, the parts 30 that form the double fold 13 and 14 are folded inwardly, as shown in Figure 2, that action being accompanied by a movement toward each other of the upper edges of the panels 11 and 12, 35 completion of the latter movement bringing about a closure of the container as already above described, excepting that the flap 15 (see Figure 3) is upstanding beyond the folded and alined top marginal portions of the folded panels or 40 parts. The container thus filled would appear in front elevation substantially as shown in Figure 1, whereupon the operator swings the flap 15 about the fold line 16 as an axis throughout substantially 180°; such swinging would take place 45 rearwardly, as viewed in Figure 1, or in clockwise direction, as viewed in Figure 3, and thereby the flap 15 is folded over the alined upper edges of the double folds 13 and 14 and of the rear panel 12, in effect also drawing these folds tightly 50 together. The parts assume the relationship shown in Figure 4, the device 17 having thereby been moved to the rear side of the container and also swung through 180°. In Figure 5 is shown 55 in cross-section how the flap 15 is folded over the now closed end of the container and also how it overlies the upper substantially alined edges of the folded parts and how the latter are thereby drawn together.

Thereupon the operator bends the lateral 60 tongues 22, 23 about a vertical axis and to the front of the upper folded closed end of the container, giving these tongues positions as better shown in Figures 6 and 7, this action resulting in tightly clamping the several thicknesses of 65 material together illustratively and as is shown in Figure 5, with the illustrative form of container employed, five thicknesses of container material are thus securely clamped between the tongue 22 and the portion 18 at one end of the 70 container and a like number of thicknesses clamped between the portion 19 and the tongue 23 at the other end of the container. The lateral tongues 22 and 23 may be made of any desired or suitable length.

75 Having thus bent the lateral tongues 22, 23, as

just described, the operator bends the still up-standing V-shaped portion 20 (see Figure 4) forwardly and throughout substantially 180° and into the position substantially as shown in Figures 6 and 7. Thereby several unique clamping and 5 securing actions are brought about. For example, at the two points of bending of the V-shaped part 20, indicated in Figures 6 and 26 and 27, two U-shaped clamping effects or structures are brought about and preferably the parts of 10 the device 17 are so proportioned that these two U-shaped clamping structures are made effective throughout the central region of the closed top portion of the container where there are, in the illustrative form of container, two thicknesses of 15 material, namely, the thicknesses of the panels 11 and 12 (Figure 2). Thus, dependable clamping is effected throughout the general central region of the folded closed end of the container, and as is best shown in Figure 6, it will be noted 20 that the opposed arm portions of each U-shaped clamping structure are divergent and thus distribute the clamping and holding actions to the right and left, as viewed in Figure 6. Thus, considering the clamping structure at the point 25 26, the arm thereof that extends to the rear side of the container 10 will be seen to extend leftwardly while the arm that comes over to the front side of the container extends toward the right, there being a reverse relationship with respect 30 to the clamping structure at the point 27. Thus, clamping pressures are dependably distributed.

The lower end of the V-shaped part 20, as seen in Figure 6, takes part in an additional closure-retaining action, and that action is better 35 shown in Figure 8. The lower end of the V-shaped part 20 is pressed inwardly or to the right, as viewed in Figure 8, and acts to bow the upper portion of the front panel 11 rearwardly toward and against the rear panel 12, in effect bowing 40 both panels rearwardly, as is indicated also in Figure 7. This action insures against loosening up, or separation from each other, of the upper end portions of the panels 11—12 and thus, in coaction with the other clamping effects above 45 described, the device 17 dependably and reliably maintains the closure of the container in closed relationship.

The container may be easily opened. The tongues 22 and 23 are unbent and restored to the 50 relationship shown in Figure 4, as is also the V-shaped part 20, the operation in unbending thus resulting in undoing the action of the part 20, as viewed in Figure 6, and also the clamping actions of the clamping structures at the points 55 26 and 27. The structure having been restored to the relationship shown in Figure 4, the device 20 is given a 180° swing or turn about the axis of the fold line 16 of the flap 15, whence the parts are restored to the relationship shown in Figure 1. 60 Thereafter the panels or like parts of the folded closure end of the container may be unfolded and the container thus opened for the discharge of its contents. Restoration of the closure-retaining device to the relationships shown in 65 Figures 6 and 7 may again, if desired, be easily accomplished.

As above noted, the device 17 appears in plan or development as it is shown in Figure 1. In Figure 9 I have indicated how a sheet or strip 70 71 of sheet material, such as sheet metal, out of which the device 17 is to be made, may be cut up, if it has a width equal to the over-all length of the device 17, as viewed in Figure 1, into devices 17, without any loss or wastage of the raw 7

material itself. Any suitable punch press dies or tools may, of course, be used to stamp or cut the devices out of the raw material.

Thus, it will be seen that there has been provided in this invention a closure-retaining device in which the various objects heretofore noted, together with many thoroughly practical advantages, are successfully achieved. It will be seen that the device is inexpensive, thoroughly dependable in use and efficient in action. Moreover, it will be seen that it is well adapted to meet the hard conditions of practical use.

As many possible embodiments may be made of the above invention and as many changes might be made in the embodiment above set forth, it is to be understood that all matter hereinbefore set forth, or shown in the accompany drawings, is to be interpreted as illustrative and not in a limiting sense.

20 I claim:

1. The combination with a container made of paper, or the like, having opposed side walls and opposed end walls, the latter being foldable against the former upon the upper end edges of the former being brought together, thereby to close said end of the container, one of said side walls having a flap extension bendable over and downwardly against the opposed side wall, said flap extension having secured thereto a closure-retaining device which comprises a sheet metal member of a width commensurate with that of said flap and having three major portions, two of which overlie said flap extension adjacent its two ends and the third comprising an intermediate V-shaped portion the apex of which extends downwardly from the line of said first two portions, whereby when said flap extension is folded over said opposed side wall and carries said device over with it, said V-shaped portion may be 40 bent back and against said flap-bearing side wall.

2. The combination with a container made of paper, or the like, having opposed side walls and opposed end walls, the latter being foldable against the former upon the upper end edges of the former being brought together, thereby to close said end of the container, one of said side walls having a flap extension bendable over and downwardly against the opposed side wall, said flap extension having secured thereto a closure-retaining device which comprises a sheet metal member of a width commensurate with that of said flap and having three major portions, two of which overlie said flap extension adjacent its two ends and the third comprising an intermediate V-shaped portion the apex of which extends downwardly from the line of said first two portions, said first two portions having lateral extensions beyond the edges of said side wall, whereby said lateral extensions, after said flap extension has been folded over said opposed side wall, may be bent to clamp between them and said respective two portions the intervening wall thicknesses of the container, and said V-shaped intermediate portion may be bent over and down against said flap-bearing side wall.

3. The combination with a container made of paper, or the like, having an otherwise open end closable by folding the end portions of the container wall together, of a sheet metal closure-retaining device comprising a sheet metal member having two end portions that have extensions beyond the ends of the container closure, said extensions being bendable therearound to hold the container wall thicknesses at the ends of the closure against separation, and an intermediate

V-shaped portion the arms of which are bendable over and beyond the top edges of the closure to hold intermediate wall thicknesses of the latter against separation.

4. The combination with a container made of paper, or the like, having an otherwise open end closable by folding the end portions of the container wall together, of a sheet metal closure-retaining device comprising a sheet metal member having two end portions that have extensions beyond the ends of the container closure, said extensions being bendable therearound to hold the container wall thicknesses at the ends of the closure against separation, and an intermediate portion forming, when bent over and beyond the top edge of said closure, two spaced clamping means for the wall thicknesses intermediate the ends of the closure.

5. The combination with a container made of paper, or the like, having an otherwise open end closable by folding the end portions of the container wall together, of a sheet metal closure-retaining device comprising a sheet metal member having two end portions that have extensions beyond the ends of the container closure, said extensions being bendable therearound to hold the container wall thicknesses at the ends of the closure against separation, and an intermediate portion of substantial length and bendable over and beyond the top edge of said closure, to hold intermediate wall thicknesses of the closure against separation.

6. A blank for a container-closure-retaining device for the clamping together of opposed container parts that form the container closure, said blank being made of sheet metal and comprising two spaced substantially aligned end portions connected by an intermediate portion that is substantially V-shaped, said device having its V-shaped portion bendable along an axis transverse to the bisector of the angle of the V so that the apex part of the V-shaped portion may rest against one of said container parts and the remaining two parts of the V-shaped portion rest against the other of said container parts to clamp said opposed container parts together.

7. A blank for a container-closure-retaining device for the clamping together of opposed container parts that form the container closure, said blank being made of sheet metal and comprising two spaced substantially aligned end portions connected by an intermediate portion that is of substantially the same width as said two spaced portions but of greater length than the spacing therebetween, said two end portions, when said device is related to said opposed container parts of a container, being bendable about the container parts to clamp said container parts together.

8. A blank for a container-closure-retaining device for the clamping together of opposed container parts that form the container closure, said blank being made of sheet metal and comprising two spaced substantially aligned end portions connected by an intermediate portion that is substantially reentrant, said end portions, when said device is related to said opposed container parts of a container, being bendable about the respective end edges of said opposed container parts to clamp them together in closing position, and said intermediate portion being bendable over said container parts intermediate of said end edges thereof to clamp said container parts together in the region intermediate of said end edges.

OSCAR W. WENTZ.
